ARTICLE TRANSFER AND RETAINER

Paul C. Bauer, Davenport, Iowa, assignor, by
mesne assignments, to American Machine &
Foundry Company, New York, N. Y., a corpora-
tion of New Jersey

Application October 12, 1950, Serial No. 189,847

7 Claims. (Cl. 198—27)

1

This invention relates to article retainers for wrapping machine elevators and particularly for elevators of the swinging type in which the article being wrapped is delivered onto the elevator platform while the platform is in an inclined position, the retainer serving to hold the article on the elevator during the upward travel of the elevator.

The retainer of the present invention is mounted beneath the platform of the elevator and is movable from a position entirely beneath the elevator platform to a position in which retaining fingers project above the top of the platform to hold an article that has been delivered onto the platform.

In elevators of the type in which the leading end of a wrapper web is clamped to the article to be wrapped as the article is delivered to the elevator and is pulled over the top of the article while the elevator moves upwardly, there may be at times considerable pull on the article tending to move the same off the elevator. The retainer of the present invention serves to firmly hold the article on the elevator until the elevator reaches its discharge position and is then automatically retracted to permit the article to be discharged from the elevator.

In wrapping machine in which the web feed mechanism is controlled by tension on the web, the operation of the wrapping mechanism is not affected by a skip in the article feed and any article delivered to the wrapping mechanism is wrapped and discharged from the machine. In any cycle in which an article is not fed to the elevator, the empty elevator is raised and lowered past the leading end of the wrapper web with its forward edge in close proximity to the web, and in order to avoid displacement of or damage to the web, the retainer of the present invention is automatically locked in its retracted position during movements of the elevator when empty.

Reference should be had to the accompanying drawings forming a part of this specification in which:

Fig. 1 is a side elevation of an elevator provided with the retainer of the present invention, the elevator being shown in full lines in an intermediate position with the retainer in article holding position, the receiving and discharging positions of the elevator being shown in dotted lines.

Fig. 2 is a fragmentary section taken on the line indicated at 2—2 in Fig. 5 showing the follower on the elevator in its forward retainer locking position.

2

Fig. 3 is a section taken on the line indicated at 3—3 in Fig. 2.

Fig. 4 is a fragmentary side elevation of the elevator in its discharge position.

Fig. 5 is a fragmentary plan view of the elevator.

The device of the present invention is shown applied to a wrapping machine provided with an endless article feed conveyor provided with flights 1 attached to sprocket chains 2 that push the articles to be wrapped along a bed 3. The feed conveyor delivers to a vertically swinging elevator which moves from a receiving position in alignment with the bed 3 to an upper discharging position where the article is delivered from the elevator to the folding and sealing channel of the wrapping machine.

The elevator is provided with a platform 4 that is attached to swinging arms 5 that are oscillated by means of cam actuated links 6 to move from the dotted line position in alignment with the bed 3 to the upper position shown in dotted lines in Fig. 1 where the article is discharged, sufficient dwell being provided in the receiving and discharge positions to permit delivery of the articles to the elevator and discharge of the article therefrom. The feed conveyor is intermittently operated and stops with the flight in the position shown in Fig. 1 while the elevator is moved upwardly past the flight. As the article is delivered to the elevator it is pushed against the leading end of a wrapper web positioned between the feed conveyor and elevator and the web is clamped between the article and a follower 7 on the elevator which is moved rearwardly as the article is pushed onto the elevator platform.

The follower 7 has a rearwardly extending bar 8 attached thereto which slides in a guide 9 mounted on the elevator platform and in order to retain the follower in the position to which it has been moved, an adjustable friction member 10 carried by the guide 9 exerts sufficient resistance to movement of the follower to hold the follower to the position to which it is moved when the article is delivered to and discharged from the elevator platform.

In its discharge position the elevator platform is aligned with the top of a paper guide roller 11 over which the article is pushed into the folding and sealing channel of the wrapping machine (not shown). The rollers 12 mounted on the underside of the platform 4 engage with the roller 11 in the discharge position of the elevator and the wrapper web passes between the rollers 11 and 12 during movement of the ar-

title from the elevator. In the discharge of the article from the elevator, the follower 7 is advanced toward the front edge of the platform as the article is pushed off the platform 4 and over the roller 11. The follower 7 remains in a position adjacent the forward edge of the platform 4 while the elevator returns to article receiving position so that the paper web is clamped between the follower 7 and the next article fed to the elevator.

Prior to or during the discharge of the article from the elevator the wrapper web is severed below the rollers 11 and 12 by means of a suitable knife which cooperates with a shear bar 13 attached to the underside of the elevator and underlying the rollers 12.

Centrally of the elevator platform between the rollers 12 there is mounted a retractable article retainer 14 having a portion that is movable to a position above the forward edge of the elevator platform 4 in front of an article on the platform to hold the article against displacement during upward movement of the elevator. The retainer moves forwardly and rearwardly through a slot 15 in the shear bar 13 and has spaced forwardly extending arms 16 provided with upwardly extending article retaining fingers 17 which are positioned in front of an article on the platform to retain it on the elevator during upward movement of the elevator. The retainer 14 is provided with axially aligned trunnions 18 that slide in channels 19 in brackets 20 attached to the under side of the elevator platform 4. The retainer 14 has a centrally disposed rearwardly projecting arm 21 that is operably connected to a transverse rock shaft 22 mounted on brackets 23 and 24 attached to the under side of the platform 4. The arm 21 is pivotally connected to the upper end of an arm 25 that is mounted for turning movement on the rock shaft 22. At the end of the shaft 22 adjacent the front of the machine the shaft has a crank arm 26 that is connected to a lever 27 that is pivotally supported intermediate its ends on the lower end of a link 28 that is pivoted at its upper end to a cross rod 29 extending across the space between the elevator arms 5. The link 28 is connected to the lever 27 by a pivot 30 and the free end of the lever 27 carries a roller 31 that is engaged while the elevator is in its lowermost article receiving position by a segment cam 32 attached to a cam shaft 33 to move the retainer to its article holding position after an article has been transferred by the elevator. The pivot 30 carries a roller 34 that engages with a trip plate 35 (see Figs. 4 and 5) attached to the machine frame and positioned to engage with the roller 34 as the elevator approaches its uppermost position.

The engagement of the segment cam 32 with the roller 31 when the elevator is in alignment with the feed conveyor bed 3 causes the arm 25 to be rocked forwardly, moving the trunnions 18 forwardly in the guide channels 19 to advance the retainer 14 to position the retaining fingers 17 beyond the forward end of the elevator platform 4 and to rock the forward end of the retainer 14 upwardly to move the fingers 17 into retaining position in front of the article that has been pushed onto the elevator by a conveyor flight 1. When the roller 34 strikes the trip plate 35 the arm 27 is swung rearwardly, rocking the retaining fingers downwardly to a position below the elevator platform and sliding the trunnions 18 rearwardly in the channels 19 to bring the retainer entirely beneath the elevator platform.

It is desirable that the retraction of the retaining fingers be positive in order to insure release of the article in the uppermost position of the elevator. It is also desirable that the mechanism moving the retaining fingers into their retaining position be yieldable so that the mechanism will not be damaged if the movement of the retaining fingers to locking position is impeded, for example, by an improper adjustment of the elevator with respect to the feed conveyor.

The arm 25 is actuated by a disk 36 fixed to the rock shaft 22. The disk has a laterally projecting pin 37 which projects in front of the arm 25 to provide positive actuation of the arm in a rearward direction to retract the retaining fingers. The supporting bracket 23 carries a spring pressed ball detent 38 that is engageable with either one of two angularly spaced recesses 39 and 40 in the adjacent face of the disk 36. The detent 38 engages in the recess 39 when the retainer is in article engaging position and with the recess 40 when the retainer is in retracted position. The detent 38 and recesses 39 and 40 provide yieldable locking means for holding the retainer in adjusted positions during vertical movements of the elevator while the rollers 31 and 34 are out of engagement with the segment cam 32 and trip plate 35.

The arm 25 carries a spring pressed ball detent 41 that is engageable in a recess 42 in the disk 36 to normally cause the arm 25 to move forwardly with the disk 36 to move the retainer to article engaging position. If, however, there is resistance to movement of the retainer to article engaging position such as might be caused by engagement of the fingers 17 with the conveyor flight, the detent 41 would yield and allow the disk to move independently of the arm 25.

It is desirable that the retainer be positively locked in its retracted position during the downward movement of the elevator so that it will be impossible for the retaining fingers to be accidentally moved to a position where they would block the entry of an article onto the conveyor platform. To this end the arm 25 is provided with a rearwardly extending projection 43 which is substantially parallel with the elevator platform when the retainer 14 is retracted.

The guide bar 8 of the article clamping follower 7 has a downwardly projecting stop member 44 attached to the underside thereof that has a forwardly projecting flange 45 that is moved to a position in which it directly overlies the projection 43 of the lever 25 when the follower is in its forward position. Upon discharge of the article from the elevator onto the discharge runway, the follower 7 is moved to its forward position and remains in this position until it is again moved rearwardly by an article pushed onto the elevator platform. The member 44 provides a positive lock which prevents actuation of the retainer during the lowering movement of the elevator and until the follower 7 is moved rearwardly by an article pushed onto the elevator. The flange 45 provides an elongated stop which is effective for various positions of the follower 7 adjacent the receiving edge of the elevator platform so that it is not necessary that the follower be always stopped in the same position.

If there should be a skip in the delivery of articles by the feed conveyor to the elevator, the follower 7 will remain in its forward position locking the retainer against movement and actuation of the lever 27 by the cam 32 will cause the

detent 41 to slip, thereby permitting the actuation of the lever 27 by the cam without causing actuation of the retainer. In the retracted position of the retainer, the fingers 17 are beneath the elevator platform and to the rear of the forward edge of the platform where they cannot engage with the leading end wrapping paper which hangs in front of the upwardly moving elevator whenever there is a skip in the feed of articles to the elevator.

It is to be understood that variations and modifications of the specific devices herein shown and described for purposes of illustration may be made without departing from the spirit of the invention.

What I claim is:

1. In a wrapping machine an elevator having an article receiving platform, an article retainer mounted on said elevator for movement from a retracted position below said platform and rearwardly of the forward edge thereof to an article retaining position in which it projects above the forward edge of said platform, means including a lever on said elevator for shifting said retainer, means for locking said retainer in retracted position, a yieldable connection between said lever and said retainer to permit actuation of the lever with the said retainer locked against movement, and means operating in timed relation to movements of the elevator for actuating said lever.

2. In a wrapping machine an elevator having an article receiving platform, an article retainer mounted on said elevator for movement from a retracted position below said platform and rearwardly of the forward edge thereof to an article retaining position in which it projects above the forward edge of said platform, means including a lever on said elevator for shifting said retainer, a positive actuating connection between said lever and said retainer for retracting said retainer upon movement of the lever in one direction, a yieldable connection between said lever and retainer for moving said retainer to article retaining position upon movement of the lever in the opposite direction, means operating in timed relation with respect to movements of said elevator for actuating said lever, and means for locking said retainer in retracted position.

3. In a wrapping machine, an elevator having an article receiving platform and mounted to swing vertically about a horizontal axis disposed rearwardly of the platform from a lower forwardly and downwardly inclined receiving position to an upper discharging position, an article retainer mounted on said elevator for movement across the forward edge of said platform from a retracted position below the forward edge of the platform to an article retaining position above the forward edge of the platform, a rotary cam having a raised peripheral portion, a stationary trip member, a lever mounted on said elevator for bodily movement therewith from a lower position in which it is disposed in the path of said raised portion of the cam to an upper position clear of said cam where it is engaged by said trip member, means for actuating said elevator and said cam in timed relation to actuate said lever while the said elevator is in its lower position, means connecting said lever to said retainer to shift said retainer to article retaining position upon actuation of the lever by said cam and to shift said retainer to retracted position upon engagement of said trip member with said lever, and means for holding said retainer in ad-

justed positions during intervals when said lever is disengaged from both the cam and the trip member.

4. In a wrapping machine, an elevator having an article receiving platform and movable from an article receiving position to an article discharging position, an article retainer mounted on said elevator for movement from a retracted position below the forward edge of said platform to an article retaining position in which it projects above said forward edge, a retainer actuating member mounted on said elevator, means connecting said actuating member to said retainer to shift the retainer to its article retaining position upon movement of said actuator in one direction and to its retracted position upon movement of the actuator in the opposite direction, said connecting means being yieldable to permit movement of said actuator relative to said retainer, means timed with respect to movements of the elevator for operating said actuator, means for locking said retainer in retracted position, means for moving an article onto said elevator platform, and means actuated by an article moving onto said platform for releasing said locking means.

5. In a wrapping machine, an elevator having an article receiving platform and movable from an article receiving position to an article discharging position, an article retainer mounted on said elevator for movement from a retracted position below the forward edge of said platform to an article retaining position in which it projects above said forward edge, a retainer actuating member mounted on said elevator, means connecting said actuating member to said retainer to shift the retainer to its article retaining position upon movement of said actuator in one direction and to its retracted position upon movement of the actuator in the opposite direction, said connecting means being yieldable to permit movement of said actuator relative to said retainer, means timed with respect to movements of the elevator for operating said actuator, means for locking said retainer in retracted position, means for moving an article onto said elevator platform, a follower slidably mounted on the elevator for movement rearwardly with an article as it is moved onto the elevator and forwardly with an article as it is moved off the elevator, and means controlled by the follower for locking said retainer in retracted position when the follower is in its forward position.

6. In a wrapping machine, an elevator having an article receiving platform and mounted to swing vertically about an axis disposed rearwardly of said platform from a lower forwardly and downwardly inclined article receiving position to an upper article discharging position, an article retainer mounted on said elevator for movement across the forward edge of said platform from a retracted position below the forward edge of the platform to an article retaining position above the forward edge of the platform, means for feeding articles onto said elevator platform, a movable locking member for holding said retainer in retracted position, a movable member in the path of an article being moved onto the elevator and connected to said locking member to move the same out of retainer locking position upon delivery of an article to said elevator, a retainer actuating member on said elevator, means timed with respect to movements of the elevator for imparting movements to said actuating member, a movement trans-

mitting connection between said retainer actuating member and said retainer, said connection being yieldable to permit said timed movements of said actuating member while the retainer is locked in retracted position.

7. In a wrapping machine, an elevator having a platform and movable from an article receiving position to an article discharging position, an article retainer having laterally spaced article retaining fingers at its forward end, said retainer being mounted on the elevator beneath said platform for bodily movements forwardly and rearwardly and for vertical rocking movements, actuating means for moving said actuator forwardly and rocking the same to move the retaining fingers across the forward edge of said platform to article retaining position and for rocking the forward end of said actuator downwardly to move said retaining fingers to a position below said platform and moving said retainer rearwardly to a retracted position where

said fingers are beneath the platform and to the rear of the forward edge thereof, means timed with respect to movements of the elevator for delivering articles to said elevator, means controlled by an article delivered to said elevator for operating said actuating means to move said retainer to article retaining position after delivery of the article to the elevator, and means for moving said retainer to its retracted position to permit discharge of an article from the elevator.
